[57] CLAIM

The ornamental design for a children's training toilet, as shown and described.

DESCRIPTION

FIG. 1 is a perspective view taken from the top, front and right side of a children's training toilet showing my new design;

FIG. 2 is a left side elevational view thereof, the right side being a mirror image of the left side;

FIG. 3 is a front elevational view thereof; and,

FIG. 4 is a rear elevational view thereof.
